UNITED STATES PATENT OFFICE.

JOSEPH A. WALSH AND JAMES F. KENNEDY, OF PITTSBURGH, PENNSYLVANIA; JAMES J. WALSH, EXECUTOR OF THE SAID JOSEPH A. WALSH, DECEASED.

TIE PLATE.

Application filed December 4, 1922. Serial No. 604,698.

To all whom it may concern:

Be it known that we, JOSEPH A. WALSH and JAMES F. KENNEDY, citizens of the United States, residing at Pittsburgh, in the 5 county of Allegheny and State of Pennsylvania, have invented certain new and useful Improvements in Tie Plates, of which the following is a specification.

Our invention relates to improvements in 10 tie plates for the rails of railway tracks, for the purpose of supporting the rails on the ties. The invention is especially designed to prevent the rails from spreading or varying from their standard gauge location, also 15 to prevent creeping, and to resist the common tendency to lift or move the securing spikes or screws from the ties.

The invention also has in view to provide 20 a tie plate of simple and economical construction, with accompanying durability and efficient resistance to the usual shocks and strains of traffic.

One preferred form of the invention is 25 illustrated in the accompanying drawings, in which:

Fig. 1 is a perspective view showing a portion of rail mounted on our improved tie plate in position on a tie;

Fig. 2 is a plan view, partly broken away, 30 showing the rails and their plates at each side of the track;

Fig. 3 is a sectional elevation of Fig. 2;

Fig. 4 is a detail view in perspective of the bottom plate;

Fig. 5 is a similar view of the top plate;

Fig. 6 is an enlarged plan view in detail, showing the lug and socket connection between the tie plate and rail flange; and

Fig. 7 is a similar view in section, showing these parts slightly separated.

The tie plate as a whole comprises a lower or bottom plate 2 and an upper or top plate 3 adapted to lie thereon. Each plate is provided with spike holes 4 and bolt holes 5, of proper shape and location to register with each other when the plates are superimposed, as in Figs. 2 and 3, for engagement with the rail flanges. In such position, spike holes 4 are in proper position for 45 driving the usual spikes to engage the flanges 6 of rail 7 and bolt holes 5 are spaced so as to allow for the driving of lag bolts, screw spikes, tie plate screws, or the like.

Each plate 2 and 3 is provided at each 50 outer side with upstanding integral lugs 8,

the lugs of bottom plate 2 being above the face of the plate a distance equal to the thickness of the upper plate, as shown. The purpose of such arrangement is so that when both plates are in position the lugs will 60 equally embrace the flanges on the same level.

Upper plate 3 is of the same width as plate 2 at its outer portion, but is reduced in width at its middle so as to extend inwardly between the lugs 8 of plate 2. The latter are provided with inwardly extending supporting bases 9, upon which the rail flanges rest, flush with the main upper surface of upper plate 3, in normal position, 70 as shown.

The flange engaging lugs 8 overlap and snugly engage the tapering edges of the rail flanges 6 and firmly hold them in place. One or both lugs 8 of each plate is provided 75 at its inner socket portion with a vertically arranged inwardly extending V-shaped tooth 10 adapted to be forced into a corresponding recess or groove 11 in the edge of the rail flange. Such grooves are cut or notched 80 into the edges of the flanges at opposite sides and in registering position for the teeth 10, prior to assembling in any convenient manner.

The lower and upper plates being laid on the tie underneath the rail and slightly apart, they are then brought sufficiently close together for partial registering of the spike holes 4 above and below. Thereupon, as the 85 spikes are driven through such holes and into the tie, the plates 2 and 3 will be drawn together. The resulting inward movement of each plate brings the lugs 8 tightly over the flanges, at the same time forcing the interlocking lugs or teeth 10 into tight engagement with the sockets or grooves 11 when the complete tie plate is closely assembled. When the spikes are driven clear in, their 90 heads also engage over the flanges in the usual manner, further securing the rail. Thereupon, the holes 5 being in register, the 95 lag bolts, screw spikes or tie plate screws are inserted through them into the tie, so that with the spikes and bolts, etc., the parts are very firmly connected.

Any tendency of the rails to rise or spring up and loosen the spikes is counteracted by the lugs 8, the effect being to impart any such movement directly to the tie in the road bed. Also, any tendency of the rails to 110

creep is prevented by the lug and notch or tooth and groove engagement 10—11. The lugs or teeth 10, as shown, are preferably slightly longer than the depth of the grooves 5 or sockets 11, so that any wear may be compensated for and the lugs kept in tight engagement with the rail flanges at all times, using new spikes, if necessary.

The construction and operation of 10 the invention will be readily understood and appreciated from the foregoing description by all those skilled in the art. It will be understood that the device may be made of steel castings or forgings, without the necessity of expensive 15 finishing or fitting, and in standard sizes to suit varying weights or shapes of rails, etc. Also, that the invention may be changed or varied in detail construction, or otherwise, 20 by the skilled mechanic within the scope of the following claim.

What we claim is:

A tie plate for rails comprising substantially flat top and bottom sections, said top section having flange engaging lugs at one 25 edge thereof in the corner portions, the opposite end of the top plate being reduced in width, projections at each corner of the bottom plate at one end thereof of a thickness equal to the thickness of the first plate, said reduced end of the top plate fitting between 30 said projections, and a flange engaging lug on each projection, said plates having registering spike holes therein at each end thereof and located between the lugs, said top section only providing the seat for a rail when laid thereon.

In testimony whereof we hereunto affix our signatures.

JOSEPH A. WALSH.
JAMES F. KENNEDY.
